(57) **CLAIM**

The ornamental design of a bezel for rack mounted device, as shown and described.

DESCRIPTION

FIG. 1 is a perspective view of the bezel for rack-mounted device wherein the housing is shown in broken lines for illustrative purposes only and forms no part of the claimed design;

FIG. 2 is a front elevation view thereof;

FIG. 3 is a top plan view thereof;

FIG. 4 is a left side view thereof; and,

FIG. 5 is a right side view thereof.

The bottom view is omitted, since it contains no ornamental features.
